UNITED STATES PATENT OFFICE.

HOWARD W. LESTER, OF HARTFORD, CONNECTICUT.

DESIGN FOR AN AUTOMOBILE-HORN.

No. 39,320.

Specification for Design.

Patented May 26, 1908.

Application filed March 14, 1908. Serial No. 421,271. Term of patent 7 years.

To all whom it may concern:

Be it known that I, HOWARD W. LESTER, a citizen of the United States, residing at Hartford, in the county of Hartford and State of Connecticut, have invented a new, original, and ornamental Design for Automobile-Horns, of which the following is a specification, reference being had to the accompanying drawings, forming part thereof.

The figure is a side view of an automobile horn showing my design.

I claim:

The ornamental design for an automobile horn as shown.

HOWARD W. LESTER
